INGHOUSE ELECTRIC & MANUFACTURING COMPANY, A CORPORATION OF PENNSYL-
VANIA

EARTH DRILLING

Application filed December 31, 1924. Serial No. 759,079.

My invention relates to systems of motor control, and it has particular relation to such systems as are employed in connection with earth-drilling and similar applications.

5 An object of my invention is to provide electrical means for varying the pressure on the drilling tool in accordance with the resistance met in the drilling operation.

Certain prior systems employ mechanical 10 devices for controlling the drilling pressure in accordance with the load, whereas, in accordance with my invention, the equipment is greatly simplified by employing two alternating-current induction motors, preferably 15 having their primary windings connected in series relation.

The first motor, which is directly connected to the line, performs the customary drilling operation, while the second motor is governed in accordance with the current traversing the first motor and operates to relieve the pressure on the drill-bit in accordance with the load conditions.

20 My invention will be best understood by reference to the accompanying drawings in which

Fig. 1 illustrates a derrick, of a familiar character, employed in connection with rotary earth drilling, to which my invention is applied.

Fig. 2 is a diagrammatic representation of the scheme of main-circuit connections embodying my invention.

Referring to Fig. 1, an induction motor 1, 25 preferably of the wound-rotor type, is connected through suitable gearing to operate a rotary table 2. A drill stem 3 is rotated by means of the table and is suspended by means of a cable 4 that is wound on a hoisting drum 5, in accordance with a familiar practice. The hoisting drum is operated by means of an induction motor 6, preferably of the high-resistance squirrel-cage type. The motor 6 operates on the principle of a "torque- 30 motor", whereby, its torque is exerted in opposition to the weight of the suspended tool 3 and it functions as a "feed" motor, in conjunction with the gravity feeding of the tool itself.

35 The primary windings 7 of the motor 6

receive energy through current traversing the series-related primary winding 8 of the drilling motor 1, as shown in Fig. 2. In order to regulate the torque developed by the motor 6, an auxiliary three-phase rheostat 9 35 is connected in shunt relation to the primary windings 7.

A rotary drilling rig is illustrated in the application of Frederic W. Hild, filed Mar. 22, 1921, Serial No. 454,451, which application 40 illustrates the details of the rotary drilling connections and the customary means of suspending the drilling tool. In accordance with my system, however, it becomes unnecessary to furnish the differential mechanism 45 illustrated in the above-identified application.

The apparatus may be assumed to be in the condition illustrated in the drawings and with the drilling motor 1 operating the table 2 in the customary manner. When normal load current flows in the primary windings 8 of the drilling motor, this value of current also traverses the primary windings 7 of the feed motor 6. By means of the rheostat 9, 50 the normal torque of the motor 6 may be so adjusted as to balance the desired portion of the weight comprising the drilling tool 3, so that proper pressure is brought to bear 55 on the drill-bit, for any given earth formation.

During the drilling operation, if an increased drilling resistance is met with, by reason of variations in the earth formation, a corresponding increase in current traversing the drilling motor likewise affects the feed motor, which tends to raise the drill 3 in extreme cases, and at least to increase the tension on the cable 4 and relieve the pressure on the drill bit.

It will be apparent to those skilled in the art that the torque of the drilling motor is about proportional to the load current, whereas the torque of the feed motor will be proportional to the square of the current. I utilize 95 this effect in accordance with my invention to establish a desirable electrical-differential relation between these two motors. That is to say, the output of the motors and the corresponding drill-pressure depends upon the 100

load resistance and, if the load current is maintained constant, the respective motor torques must assume a definite relation to one another.

5 Additional weight is, of course, added to the drill as the depth of the drilling hole increases, and variations of torque required in the feeding motor are obtained by adjusting the rheostat 9.

10 Other modifications of my invention may occur to one skilled in the art. I have illustrated my invention in simple form to set forth what I believe to be a new combination and a new application of alternating-current motors for various drilling operations. I do not desire to be limited to earth drilling, since my invention may be readily adapted for other similar applications.

I claim as my invention:

20 1. In an earth-drilling system, the combination with a drilling tool, and an alternating-current induction motor therefor having a primary winding, of a second induction motor having a primary winding in series relation with the primary winding of the first-named motor for controlling the effect of said first motor.

25 2. In an earth-drilling system, the combination with a drilling tool, an alternating-current tool-driving motor having a rotor winding and a stator winding, an alternating-current tool-feeding motor having a rotor and a stator winding and means for connecting the stator windings of said motors in series.

30 3. In an earth-drilling system, the combination with a drilling tool, an alternating-current tool-driving motor provided with a plurality of windings, a second alternating-current tool-feeding motor provided with a plurality of windings, a source of alternating-current power and means for connecting certain of the windings of each of said motors in series-circuit relation directly to said source of power.

35 4. In an earth-drilling system, the combination with a drilling tool, an alternating-current tool-driving motor and an alternating-current tool-feeding motor, a circuit for energizing said motors including a winding of said first named motor and a winding of said second named motor connected in series circuit relation and directly connected to the circuit for energizing said motors and a rheostat connected to said circuit between the windings of said motors.

In testimony whereof, I have hereunto subscribed my name this 24th day of November, 1924.

60 STANLEY G. NOTTAGE.
